DESIGN FOR A TOILET POWDER CONTAINER

Laurence J. Colwell, New York, N. Y., assignor to Charles of the Ritz, Inc., New York, N. Y., a corporation of Delaware

Application December 17, 1940, Serial No. 97,400

Term of patent 14 years

To all whom it may concern:

Be it known that I, Laurence J. Colwell, a citizen of the United States, residing at New York, in the county of New York and State of New York, have invented a new, original, and ornamental Design for a Toilet Powder Container, of which the following is a specification, reference being had to the accompanying drawing, forming part thereof.

In the drawing:

Fig. 1 is a front elevational view of a toilet powder container, showing my new design;

Fig. 2 is a side elevational view thereof.

Fig. 3 is a top plan view of the container.

The ornamentation adjacent the upper edge of the container is symmetrical and circum-scribes the outer wall of said container. The ornamentation appearing on the central part of the container occurs on the front, rear and side walls.

I claim:

The ornamental design for a toilet powder container, as shown and described.
